INVENTOR:
Arthur E. James.
by *Paul S. Gooding*, Atty.

UNITED STATES PATENT OFFICE

ARTHUR E. JAMES, OF AUBURN, RHODE ISLAND

DIVISION FOR BOWLING ALLEYS AND GUARD THEREFOR

Application filed December 26, 1931. Serial No. 583,282.

This invention relates to an improved division and guard for a bowling alley.

Bowling alleys as ordinarily constructed consist of a plurality of alleys, each alley having gutters on its opposite sides to receive the balls that leave the alley, and between the alleys a division is provided consisting of a plank extending upwardly above the upper surface of the alley or gutter for several inches. These divisions are made of planks and are subject to injury, splintering, and the like, from impact thereagainst of the balls which are being bowled, necessitating the replacement of the divisions by new planks.

It is the object of this invention to protect and render more serviceable these divisions, both along the opposite faces thereof and also the front ends.

The invention consists in a division for bowling alleys and a division guard, as hereinafter set forth in the specification and particularly pointed out in the claims.

Referring to the drawing:

Fig. 1 is a side elevation of the front end portion of my division with the guard positioned at the front end of said division, the boards of the alley and approach being shown in section.

Fig. 2 is a central longitudinal sectional elevation of the front portion of the division and its end guard.

Fig. 3 is a transverse section taken on line 3—3, Fig. 1.

Fig. 4 is a rear elevation of the division guard.

Like numerals refer to like parts in the several views of the drawing.

In the drawing, 5 is a division for bowling alleys comprising a plank 6 and a metal casing 7 consisting of a top 8 extending across the upper edge of the plank 6, and sides 9 which extend along the side faces of the plank 6, the lower edge portions of said sides 9 projecting below the upper surface of the floors 10 of the adjacent alleys.

11 is a division guard for the end of the division and comprises a metallic cap provided with a chamber 12 adapted to receive one end of the division 5. The guard 11 em-

bodies a top 13 and side plates 14, the top 13 being inclined downwardly and forwardly at 15 and terminating at its lower end in an angular flange portion 16 consisting of a vertical flange 17 and a horizontal flange 18. 55 The flange 18 projects beneath the boards 19 of the approach to the alley and the said boards abut against the flange 17.

A pin 20 preferably integral with the guard 11 projects from the inclined portion 15 within the chamber 12 into the end of the division 5, thus the guard is firmly held in position by the pin 20 and the flange 16 without its being necessary to fasten the same to the floor of the alley by screws. The extreme 60 upper portion of the guard 11 terminates in a flange 21 which projects over the top 8 of the casing 7, while the rear edge portions of the sides 14 of the guard project over the sides 9 of the metal casing of the division, 70 thus clamping the front end of the metal casing 7 to the front end portion of the plank 6. 65

It will be seen that the top and sides of the plank 6 are fully protected against impact of the ball by the casing 7 and that the end of the plank is fully protected by the guard 11, thus 75 eliminating injury to the plank forming the division, both along its sides and also its front end.

I claim:

1. A division guard for bowling alleys comprising a metallic cap provided with a chamber adapted to receive one end of the division of a bowling alley, and a horizontal flange extending across the front end of the guard 85 and adapted to project beneath the floor boards of the alley approach.

2. A division guard for bowling alleys comprising a metallic cap provided with a chamber adapted to receive one end of the division of a bowling alley and embodying a top and side plates, and a horizontal projection on the inside of said top adapted to project into said division end.

3. A division guard for bowling alleys comprising a metallic cap provided with a chamber adapted to receive one end of the division of a bowling alley and embodying a top and side plates, a horizontal projection inside of said top adapted to project into said division 95 100

end, and a horizontal flange extending across the front end of said guard and adapted to project beneath the floor boards of the alley approach.

4. A division guard for bowling alleys comprising a metallic cap provided with a chamber adapted to receive one end of the division of a bowling alley and embodying a top and side plates, said top plate being inclined downwardly and forwardly and terminating at its lower end in an angular flange portion adapted to abut against and project beneath the floor boards of an alley approach.

5. A division for bowling alleys comprising a plank extending longitudinally of said alleys, a metal casing extending across the upper edge of said plank and along the side faces thereof, and a metallic guard provided with a chamber adapted to receive one end of said division and clamp the metal casing thereof to the plank.

6. A division for bowling alleys comprising a plank extending longitudinally of said alleys, a metal casing extending across the upper edge of said plank and along the side faces thereof, a metallic guard provided with a chamber adapted to receive one end of said division and clamp the metal casing thereof to the plank, and a horizontal flange extending across the front edge of the guard and adapted to project beneath the floor boards of the alley approach.

In testimony whereof I have hereunto set my hand.

ARTHUR E. JAMES.
